WEDGIE TYPE SHOE

Thomas E. Neal, Chicago, Ill.

Application July 24, 1947, Serial No. 763,288

4 Claims. (Cl. 36—1)

1

The present invention relates to shoes of the wedge heel type, and more particularly to such shoes of the high heel-platform inner sole variety.

It is a general object of the present invention to provide a shoe of improved construction and arrangement rendering it both of novel design and of additional functional utility.

Another object of the invention is to provide in a shoe of the wedge heel type a compartment having a closure member affording access to the compartment and lending attractive appearance to the shoe.

A further object of the invention is to provide a combination shoe and safe for valuables or other articles.

Further features of the invention pertain to the particular construction and arrangement of the shoe; whereby the above outlined and additional features thereof are attained.

The invention, both as to its organization and method of operation, together with further objects and advantages thereof, will best be understood by reference to the following specification, taken in connection with the accompanying drawing, in which Figure 1 is a side elevational view, taken from the inside, partly broken away, of a shoe, illustrating the door thereof in closed position, and embodying the present invention; Fig. 2 is a fragmentary side elevational view of the shoe, shown in Fig. 1, illustrating the door thereof in open position; and Fig. 3 is a fragmentary lateral sectional view of the shoe, taken in the direction of the arrows along the line 3—3 in Fig. 1.

Referring now more particularly to Figs. 1 to 3, inclusive, of the drawing, the shoe 10 there illustrated, and embodying the features of the present invention, is of the high wedge heel-platform inner sole type comprising an upper 11 of the open-toe slipper variety, an ankle strap 12, a substantially flat outer sole 13, an inner sole 14 and an interposed platform 15. The ball-supporting surface 14a of the inner sole 14 is spaced above and substantially parallel to the corresponding surface of the outer sole 13; and the arch-supporting surface 14b and the heel-supporting surface 14c of the inner sole 14 are spaced above and sharply rearwardly inclined with respect to the corresponding surfaces of the outer sole 13; whereby the platform 15 terminates in a wedge-shaped portion 15a disposed below the arch-supporting surface 14b and the heel-supporting surface 14c of the inner sole 14.

A compartment 16 is formed in the wedge-shaped portion 15a of the platform 15 and dis-

posed below the arch-supporting surface 14b of the inner sole 14 and extending, at least partially, below the heel-supporting surface 14c of the inner sole 14; which compartment 16 is provided with an opening 16a affording access thereto and extending through the inside side-wall of the platform 15. The outline of the opening 16a conforms generally to that of the wedge-shaped portion 15a of the platform 15 in order to lend an attractive design to the inside side-wall of the platform 15 and to break-up the apparent expanse of the inside side-wall of the platform 15. A liner 17 is arranged within the compartment 16 and conforms to the wall surface thereof; the liner 17 including a substantially horizontal bottom wall 18, a substantially vertical end wall 19, a connecting arcuate-shaped combination top and end wall 20 and a rear wall 21. The liner 17 may be formed of metal, of 20 molded plastic, or of any other suitable material; and is preferably presesd into firm engagement with the walls of the platform 15 surrounding the compartment 16 formed therein; whereby the liner 17 constitutes a finished shell lining the 25 compartment 16 and adapted to receive valuables or other articles. Preferably, the inside marginal edges of the bottom wall 18, the end wall 19 and the combination top and end wall 20 disposed adjacent to the opening 16a formed in the inside 30 side-wall of the platform 15 terminate a short distance below the inside side-wall of the platform 15. Finally, a closure member 22 in the form of a door conforming to the configuration of the opening 16a formed in the inside side-wall 35 of the platform 15 is hinged adjacent the rear edge thereof to the adjacent edge of the end wall 19 of the liner 17 by an arrangement including two hinges 23; the pintles of the hinges projecting slightly beyond the door 22 and the adjacent inside side-wall of the platform 15 in order 40 to lend additional ornamentation. When the door 22 occupies its closed position, the outer-surface thereof is disposed substantially flush with and merging into the inside side-wall of the platform 15 to provide a finished appearance. Moreover, the inner surface of the door 22 disposed adjacent to the boundary thereof engages the adjacent marginal edges of the bottom wall 18, the end wall 19, and the combination top and 45 end wall 20 in order to seal the compartment 16 formed within the liner 17. Finally, the inner surface of the door 22 adjacent to the forward edge thereof carries a lock 24 provided with a retractable latch 25 adapted to cooperate with 50 a keeper 25a, carried on the adjacent inner sur-

face of the combination top and end wall 29 in order to retain the door 22 in its closed position. Also the door 22 has a keyhole 26 formed therein through which a key 27 may be inserted into the lock 24 in order to retract the latch 25 when it is desirable to unlock the door 22 and move it to its open position. The key 27 may be permanently secured by a wire, cord or the like 28, to the end of the ankle strap 12 in order further to lend ornamentation to the shoe 10.

Of course it will be understood that the general outline of the compartment 16 formed in the wedge-shaped portion 15a of the platform 15 may be varied so that the conforming door 22 may have other ornamental configurations. Moreover, a latch mechanism may be substituted for the lock mechanism 24 and provided with a thumb bolt for retracting the latch 25, thereby eliminating the necessity of the key 27. Finally, it will be understood that the outer surface of the platform 15 and the outer surface of the door 22 are provided with a covering of leather, fabric or other ornamental material in accordance with conventional design; which material may be the same as that of the upper 11 and the ankle strap 12 or contrasting therewith in accordance with the usual flexibility of design factors. Finally the platform 15, the door 22, the upper 11 and the strap 12, or any one or combination thereof, may carry other ornamentation.

The arrangement of the opening 16a into the compartment 16 through the inside side-wall of the platform 15 is very advantageous in view of the fact that ready access may be gained into the compartment 16 by a woman wearing the shoe merely by crossing her legs. Also this position of the opening 16a into the compartment 16 causes the door 22 to occupy a position wherein the key 27 may be readily inserted through the key hole 26 into the lock 24 in order to retract the latch 25. The volume of the compartment 16 may be considerably varied, although it is contemplated that it be large enough to receive a woman's coin purse as well as her cosmetic accessories. Of course, the construction and arrangement above described may be incorporated in an evening shoe, a beach shoe or general-purpose shoe; however, it is considered to be highly advantageous when incorporated either in an evening shoe or in a beach shoe.

In view of the foregoing, it is apparent that there has been provided a combination shoe of the high wedge heel platform inner sole type and safe for valuables or other articles; wherein the door to the compartment formed in the safe is arranged to lend ornamental design to the inside side-wall of the platform.

While there has been described what is at present considered to be the preferred embodiment of the invention, it will be understood that various modifications may be made therein, and it is in-

tended to cover in the appended claims all such modifications as fall within the true spirit and scope of the invention.

What is claimed is:

- 5 1. In a shoe of the wedge heel type including a substantially wedge-shaped platform arranged between the inner sole and the outer sole thereof and disposed below the heel-supporting surface and the arch-supporting surface of the inner sole; 10 said platform having a compartment formed therein disposed below the arch-supporting surface of the inner sole, the inside sidewall of said platform having an opening formed therein communicating with said compartment, and a hinged 15 cover for closing said opening.
- 20 2. In a shoe of the wedge heel type including a substantially wedge-shaped platform arranged between the inner sole and the outer sole thereof and disposed below the heel-supporting surface and the arch-supporting surface of the inner sole; 25 said platform having a compartment formed therein disposed below the arch-supporting surface of the inner sole, the inside sidewall of said platform having an opening formed therein communicating with said compartment, a frame arranged within said opening, and a hinged cover for closing said opening carried by said frame.
- 30 3. In a shoe of the wedge heel type including a substantially wedge-shaped platform arranged between the inner sole and the outer sole thereof and disposed below the heel-supporting surface and the arch-supporting surface of the inner sole; 35 said platform having a compartment formed therein and communicating with the exterior through an opening formed in the inside sidewall thereof, a liner arranged within said compartment and terminating in a frame surrounding said opening, and a hinged cover carried by said frame and merging with the inside sidewall of said platform when in closed position.
- 40 4. A shoe comprising a sole, a shank, a heel, a bridge connecting said sole with said heel, said shank, heel and bridge defining a compartment in a transverse relation with the shoe, a wall at one side of the shoe connecting said shank, heel and bridge, said wall defining one end of said compartment, and a movable closure at the opposite side of the shoe disposed between said shank, heel and bridge, said closure being receivable at the opposite end of said compartment.
